UNITED STATES PATENT OFFICE.

WILLIAM S. HARLEY AND ADAM ZISKA, JR., OF MILWAUKEE, WISCONSIN, ASSIGNEES
TO HARLEY-DAVIDSON MOTOR CO., OF MILWAUKEE, WISCONSIN, A CORPORATION
OF WISCONSIN.

MOTOR CYCLE.

Application filed November 1, 1919, Serial No. 335,004. Renewed February 27, 1924.

To all whom it may concern:

Be it known that we, WILLIAM S. HARLEY and ADAM ZISKA, Jr., citizens of the United States, residing at Milwaukee, in the county 5 of Milwaukee and State of Wisconsin, have invented new and useful Improvements in Motor Cycles, of which the following is a specification.

This invention relates to motor-cycles.

10 Motor-cycle frames are usually made of seamless steel tubing which is fitted and brazed to forgings at numerous points in the frame structure. The inherent temper or stiffness of the seamless drawn tubing is destroyed or lessened, at the places where the brazing takes place, and cannot subsequently be restored. Crystallization, due to vibration, begins more readily at these places than in the untreated portion of the tubing, and 15 the strength of the frame as a whole is lowered to that of these weakened parts.

Also, the changes from tubing to forgings at numerous points throughout the frame, materially detracts from the harmonious and 20 pleasing appearance.

This invention is designed to overcome these defects, and to produce a motor-cycle of improved characteristics.

One of the objects of this invention is to 25 simplify the construction of motor-cycles.

A further object is to increase the strength of motor-cycles.

A further object is to increase the durability of motor-cycles.

30 A further object is to prevent the lowering of original temper and stiffness of the metal of which the frame is composed.

A further object is to prevent rapid crystallization of the metal of which the 35 frame is composed.

A further object is to retain all of the original strength of the metal in the finished frame.

40 A further object is to increase the original temper of the metal by the methods employed in forming the frame.

A further object is to eliminate the angular corners and unsightly projections of 45 motor-cycle frames and to provide a motor-cycle frame both harmonious and pleasing in appearance, and of such proportions as to adequately carry the stresses impressed thereon.

50 A further object is to provide a motor-cycle frame which is composed of members

which are integral throughout their extent from the front fork journal to the rear axle plate.

A further object is to provide a pressed steel frame for motor-cycles.

A further object is to provide a motor-cycle frame proportioned throughout to the stresses to be borne.

Other objects will appear.

The invention contemplates, in its preferred embodiment, complementary channel members which are integral throughout, and means formed thereon for supporting an engine and fuel tank.

An embodiment of this invention is shown 70 in the accompanying drawings.

The views of the drawing are as follows:

Fig. 1 is a view of the motor-cycle embodying the invention.

Fig. 2 is a plan view of the frame.

Fig. 3 is a side view of the frame.

Fig. 4 is a side view of the main members of the frame with all other parts omitted.

Fig. 5 is a section on the line 5—5 of 80 Fig. 4.

Fig. 6 is a section on the line 6—6 of Fig. 4.

Fig. 7 is a perspective view of the brace and seat support.

Fig. 8 is a side view of the brace and seat support with the springs for the seat attached.

Fig. 1 shows the complete motor-cycle, comprising a front fork 1, a front fork 90 journal 2, a frame 3, and rear axle plates, or supports, 4. The engine and associated mechanism is suspended from four arms which are integral with, and depend from the main frame. There are two front arms 95 5 and two rear arms 6; one front and one rear arm being formed from each of the main frame members.

Figs. 2 and 3 show the frame, which comprises a pair of complementary right and 100 left hand channel members 7 which are riveted at one end, to the front fork journal 2, and at the other end to the rear axle supporting plates 4. Between these points the frame members 7 are integral throughout. Between the members 7, the gasoline tank 8 is carried, which, by being bolted to the members 7 and fitting the inner contour of such members, forms an effective brace and spacer. The cross bracing is fur- 110

ther secured by means of a bracing and seat supporting plate 9 whose curved flanges are fitted to the top flanges of the members 7 and riveted thereto. Adjacent the point 5 where the rear fork begins to form, an additional, channel shaped, cross brace 10 is provided and riveted to lugs 11 formed upon the upper and lower flanges of the members 7. Upon the brace 10, lugs 12 are provided 10 to which the rear mud guard is riveted.

Figs. 4, 5 and 6 are views of the frame members 7. The members 7 are tapered and of channel shape with upper and lower inwardly directed flanges 13 and 14, respectively, and a central web. The depth of these frame members 7 gradually decreases from the central portion to the front and rear ends, thereby providing greatest strength at the place where the greatest 15 strains occur. Two lugs 5 and 6 extend downwardly from each frame member 7 and are themselves channel shaped, with their front and rear flanges 15 inwardly directed. The members 5 and 6 are provided 20 with suitable openings 16 for receiving the bolts for attaching the engine and associated parts. A boss 17 is formed on one of the members 7 for receiving the pivot for the gear shift lever.

30 Figs. 2 and 3 show the front fork journal 2 and rear axle plates attached to the frame members 7. The front fork journal has a hollow wedge shaped, rear portion which accurately fits the inner portion of 35 the members 7 and is riveted thereto at its top, sides, and bottom portion.

The rear axle plates are slotted to receive the rear axle fastenings and are provided with lugs for the attachment thereto 40 of the mud guard, support, and a side car. The forward portion 19 of these plates 4 are channel shaped with upper and lower flanges which taper towards the forward end. These portions are fitted within the channel 45 frame members 7 and are riveted thereto at their side, top, and bottom.

A bracket 20 is attached to each arm 5 and extends forwardly, downwardly, and outwardly. The outwardly extending arms 50 21 form a support for the foot boards 22 (Fig. 1), being attached thereto by threaded pins 23 which are brazed to the arms 21.

Figs. 7 and 8 show the cross brace and seat support 9. This member has a raised 55 forward portion 24 to which is secured a rearwardly extending seat spring 25. At an intermediate point on the spring a support 26 is provided, which is adapted to be adjustably secured in a channel 27 formed 60 in the member 9.

The frame dips downwardly from its front end, increases in depth and extends substantially horizontally at its middle portion, and finally bends downwardly on a 65 long radius curve, tapering gradually to-

wards its rear end. Throughout its extent the frame is free from abrupt changes of configuration, sharp corners, and angular outline. As a whole the frame presents a pleasing, harmonious appearance, and gives 70 the effect of a unitary structure as distinguished from the other types of motorcycles in which each element, of the composite frame, stands out, distinct and separate.

75 In addition to the good appearance and increased strength secured by this type of frame, such a frame may readily be stamped and formed. It may be blanked out in one press and formed in another, thereby 80 greatly lessening the operations necessary to produce a motor-cycle frame, and retaining and, in fact, even enhancing its original temper, strength, and stiffness by the working it receives in forming.

85 Obviously other structures may be devised which will embody the invention herein set forth.

What is claimed is:

1. A motorcycle comprising a front journal 90, rear axle supports, a pair of complementary channel members connecting the journal and axle supports, and an engine suspended from and positioned below the channel members.

95 2. A motorcycle, comprising a front fork journal, rear axle supports, and a frame having complementary channel members extending in unbroken continuity from the front fork journal to the axle supports, the middle of said frame members lying in a substantially horizontal plane with one end extending upwardly at an oblique angle and the other end extending downwardly at an oblique angle.

100 3. A motorcycle, comprising a front fork journal, rear axle supports, and a frame having complementary channel members extending in unbroken continuity from the front fork journal to the axle supports, a portion of the frame members intermediate the ends thereof being arranged in a substantially horizontal plane, one end thereof extending upwardly towards the front fork and the other end extending downwardly towards the rear axle.

105 4. In a motorcycle having a front fork journal and rear axle supports, a compressed steel frame comprising a pair of complementary channel members extending from the front fork to the axle supports, each member being integral throughout its length and having a substantially horizontal portion, an upwardly extending portion at one side of the horizontal portion and a downwardly extending portion at the other side thereof.

110 5. A motorcycle, comprising a front fork, a rear axle support, a pair of complementary members extending from the front fork to

the axle support, and a fuel tank enclosed wholly within the complementary members.

6. A motorcycle, comprising a front fork, rear axle supports, a pair of members, each integral throughout its length connecting the fork and supports, a brace extending between the members and rigidly fastened thereto, and a seat mounted on the brace.

7. A motor-cycle comprising a front fork journal having a rearwardly extending portion, a pair of rear axle supporting plates, a pair of complementary channel members secured to the rearwardly extending portion of the journal and to the rear axle plates, and a seat supported solely by the channel members.

8. A motor-cycle comprising a front fork journal, a pair of rear axle plates, a rectangular frame extending from said journal to said plates, said frame comprising two opposed channel members each integral throughout the entire length of the frame, and a fuel tank enclosed entirely within the channel members.

25 9. A motor-cycle comprising a front fork journal, rear axle supports, an engine, a frame composed of a pair of opposed channel members each extending from said journal to said supports and unbroken throughout, and a depending arm formed upon each channel member for supporting said engine.

30 10. A motor-cycle comprising a front fork journal, rear axle supports, a pressed steel

frame composed of a pair of opposed channel members extending in unbroken continuity from the front fork journal to the rear axle supports, and a fuel tank enclosed within the channel members. 35

11. A motor-cycle frame comprising a pair of pressed steel channel members extending substantially the entire length of the body of the motor-cycle, each of said channel members being integral throughout and comprising upper and lower flanges, an intermediate web, and a pair of downwardly 45 extending arms.

12. A motorcycle frame, comprising a front fork, rear axle supports, a pair of channel members extending in unbroken continuity from the fork to the supports, a fuel 50 tank enclosed within the channel members, and a seat supported by the members.

13. A motorcycle frame, comprising a front fork journal, rear axle supports, a pair of complementary frame members extending 55 between the front fork and axle supports, the middle of the complementary members lying in a substantially horizontal plane with one end thereof extending upwardly towards the front fork journal and the other 60 end extending downwardly towards the rear axle supports.

In witness whereof, we have hereunto subscribed our names.

WILLIAM S. HARLEY.
ADAM ZISKA, Jr.
